INFANT'S SLEEPING GARMENT AND COVER

Marjorie L. Klein, Los Angeles, Calif.

Application August 12, 1949, Serial No. 109,890

1. Claim. (Cl. 128—134)

1

My invention relates to sleeping garments for infants and has for its principal objects, to provide a simple, inexpensive garment especially designed to be worn by infants and young children while sleeping in cribs, beds, cots and the like, and to combine with said garment a small blanket of such size and shape as to cover and thereby afford warmth and protection to the wearer of the garment and further, to provide said garment and cover with means, preferably flexible ties, adapted to be secured to the sides of the crib or bed, thus preventing the infant from falling out of the crib or bed, from kicking or pulling the garment and cover off and at the same time, giving complete freedom of movement to the infant's body within the garment, likewise to the arms and hands.

A further object of my invention is, to provide the garment with a transverse strip or panel connected to the lower end of the covering member and adapted to fold over the upper edges of the crib or bed covers, after same have been placed over the garment and its cover, thus preventing the infant from pulling the crib or bed covers up over its head and face.

A further object of my invention is, to provide simple and effective means for firmly attaching to the cover of the garment, a separate cover such as a blanket or quilt, thus assuring ample warmth for the occupant of the garment.

With the foregoing and other objects in view, my invention consists in certain novel features of construction and arrangement of parts which will be hereinafter more fully described and claimed and illustrated in the accompanying drawing in which:

Fig. 1 is a front elevational view of my improved garment.

Fig. 2 is a front elevational view of the garment with its cover and the bed clothes holding strip or panel, in folded position for use.

Fig. 3 is an enlarged vertical section taken on the line 3—3 of Fig. 1.

Fig. 4 is an enlarged vertical section taken on the line 4—4 of Fig. 1.

Fig. 5 is an elevational view showing a separately formed blanket detachably secured to the covering member of the garment.

Referring by numerals to the accompanying drawing which illustrates a preferred embodiment of my invention, 10 designates the main body of the garment which has the general shape of a conventional night gown or slumber robe and which includes sleeves 11, a neck and head

2

opening 12 and a vertically disposed button and button hole closed front opening 13 extending downward from said neck opening.

The lower end of this garment is closed after the manner of a sleeping bag and secured to said lower end, is the upper edge of a blanket-like cover 14 composed of one or more layers of suitable fabric and which when folded upward overlies garment 10 up to the sleeves 11.

Secured to the lower side corners of garment 10 and to the upper corners of blanket 14 are flexible tapes 15 and similar tapes 16 are secured to the lower corners of said blanket. These tapes serve as ties to detachably attach the garment and cover to the sides of the crib or bed occupied by the wearer of the garment.

Secured to the lower edge of covering member 14 is a transverse panel or strip 17 of one or more layers of fabric, preferably stitched or quilted to give it a certain degree of stability, and secured to the lower corners thereof are ties 18, similar to ties 15 and 16.

In use, the child after being placed in the garment 10, is laid in the crib or bed, and cover 14 is now turned upward so as to cover the greater portion of the wearer's garment-enclosed body and tapes 15 and 16 are now tied to the sides of the crib or bed so as to retain occupant therein but at the same time, permitting a substantial degree of rolling or twisting movement of the garment-enclosed body, from one side to the other beneath cover 14.

In the event that conventional bed clothes are needed to give additional warmth to the sleeping infant, said bed clothes are pulled up so as to wholly overlie cover 14 and strip 17 is now folded down over the upper edge of said bed clothes and when tapes 18 are tied to the sides of the crib or bed, the covered infant will be unable to grasp the bed clothes and pull same upward over the face or head.

In Fig. 5, I have shown an extra separate covering member or blanket 19, of the same size as cover 14 and to detachably connect this extra cover, the corners and sides thereof are equipped with the socket members 20 of conventional snap fasteners, the stud members 21 of which are secured to the corners and sides of cover 14.

Thus, it will be seen that I have provided an infant's sleeping garment and cover which is simple in structure, inexpensive of manufacture and very effective in performing the functions for which it is intended.

The garment affords warmth and comfort to the

infant, permits freedom of movement of the wearer's body and arms while covered, cannot be kicked off or pulled up over the head, prevents the wearer from falling off the bed or crib, can be used during warmer temperatures without any other coverings or blankets, thus effecting a material saving in the laundering of separate coverings and provides a substantial factor of safety and comfort for infants during their sleeping and rest periods.

Minor changes in the size, form and construction of the various parts of my improved infant's sleeping garment and cover may be made and substituted for those herein shown and described without departing from the spirit of my invention, the scope of which is set forth in the appended claim.

I claim as my invention:

In an infant's sleeping garment and cover, a body and arms covering garment closed at its lower end, a body covering member permanently secured to the lower end of said body and arms covering member, and extending the full width

thereof, a transversely disposed reinforced strip of flexible material secured directly to the lower edge of the body covering member, and adapted to be turned downward so as to overlie the upper portion of an extra cover placed on the body covering member when the same is turned upward, ties secured to the lower end of the body and arms covering member, ties secured to the lower end of said body covering member, and ties secured to the lower corners of said reinforced strip.
